CLAIM

The ornamental design for an orthosis as shown and described.

DESCRIPTION

1. Orthosis

1.1: Back shows a rear view of the orthosis;

1.2: Rear view in use;

1.3: Front shows a front view thereof;

1.4: Front view in use;

1.5: Bottom shows a bottom view;

1.6: Perspective shows a rear perspective view thereof;

1.7: Perspective shows a side perspective view;

1.8: Top shows a top perspective view; and

1.9: Side view in use.

The claimed design shows an orthosis.

In the drawings, the broken lines depict portions of the orthosis and form no part of the claimed design. The broken

(Continued)

lines showing a hand in reproductions 1.2, 1.4, 1.9 depict environmental subject matter and form no part of the claimed design.
